DESIGN FOR A BOAT

Walter T. Gassaway, Sacramento, Calif.

Application March 29, 1939, Serial No. 83,909

Term of patent 14 years

To all whom it may concern:

Be it known that I, Walter T. Gassaway, a citizen of the United States, residing at Sacramento, in the county of Sacramento and State of California, have invented a new, original, and ornamental Design for a Boat, of which the following is a specification, reference being had to the accompanying drawing, forming part thereof.

I claim:

The ornamental design for a boat, as shown.

W. T. GASSAWAY.
